UNITED STATES PATENT OFFICE

VICTOR E. EXTROM AND PETER J. N. MILLER, OF MINNEAPOLIS, MINNESOTA

TIME SWITCH

Application filed January 18, 1928. Serial No. 247,631.

This invention relates to control means for electric circuits, particularly when such circuits are supplied to toasters and other electric cooking devices required to operate for a given time and then have the current cut off.

The invention provides an electric circuit control in the nature of a time switch and including a magnetic governor to retard the movement of the timing mechanism, said governor, in the preferred form, consisting of a disc of metal and an electromagnet which, when energized exerts a retarding influence on the disc and indirectly on the switch.

While the drawings illustrate a preferred embodiment of the invention, it is to be understood that in adapting the means to meet specific needs and requirements, the design may be varied, and such other changes in the minor details of construction may be resorted to within the scope of the invention as claimed, without departing from the spirit thereof.

For a full understanding of the invention and the merits thereof, reference is to be had to the following description and the drawings hereto attached, in which,—

Figure 1 is a front view of an electric time switch embodying the invention.

Figure 2 is a vertical sectional view of the casing showing the enclosed parts in elevation.

Figure 3 is an elevational view partly in section showing the switch open.

Figure 4 is a view similar to Figure 3, showing the switch closed.

Figure 5 is a detail sectional view on the line 5—5 of Figure 2.

Figure 6 is a detail sectional view on the line 6—6 of Figure 2, looking to the left as indicated by the arrows.

Figure 7 is a fragmentary sectional view on the line 7—7 of Figure 3.

Corresponding and like parts are referred to in the following description and designated in the several views of the drawing by like reference characters.

The device includes a case 1 which encloses the working parts. The switch proper in-

cludes spaced contacts 2 which are fixed, and a movable contact 3. The movable contact 3 is mounted upon a member 4 which consists of a bar arranged to have a limited vertical or longitudinal movement. Pins 5 or other suitable fastening means retain the member 4 in place, and direct it in its longitudinal movement. The pins or fastenings 5 operate in slots formed in the member 4, and engage a plate of the frame 6 supporting the time mechanism. A spring 7 connected to the frame 6 normally exerts a downward pressure upon the member 4 to hold the switch open. A pivoted latch 8 is provided to cooperate with the member 4 to hold the switch in closed position, as indicated most clearly in Figure 4 of the drawings. This latch has an offset extension adapted to be engaged by means of a stop 9, whereby the latch is tripped and the member 4 released to admit of automatic opening of the switch and a breaking of the electric circuit controlled thereby.

A timing mechanism controls the automatic opening of the switch, and includes a train of gearing which is mounted in the frame 6. This train of gearing includes two principal shafts 10 and 11, the shaft 10 projecting at one end beyond the case 1, and having a finger piece 12 at the projecting end. The numeral 13 denotes a power spring, one end of which is secured to the shaft 10 and the opposite end connected to the frame 6. A gear wheel 14 is loose upon the shaft 10 and carries a pawl 15 which coacts with the ratchet wheel 16 fast to the shaft 10 to form connecting means between the gear wheel 14 and the power shaft 10. A cam 16a is fast to the shaft 10 and receives the offset end 17 of the member 4. This cam 16a also receives the stop 9 which trips the latch 8 to effect disengagement thereof from the member 4 to admit of automatic opening of the switch. A disc 18 is fast to the shaft 11 and preferably consists of aluminum or other metal which is amenable to magnetic influence. The numeral 19 denotes an electromagnet which is disposed with its core perpendicular to the disc 18 and close thereto to exert a retarding influence upon the disc when the electromagnet is vitalized, thereby governing the speed of the gearing and the

action of the switch. A U-shaped frame 19a is connected to one end of the core and its opposite end is spaced from the other end of the core. The spaced ends of the core and frame 5 constitute poles between which the disk 18 passes. A latch 20 pivoted to the finger piece 12 is adapted to be engaged with a stop 21 to hold the switch closed for an indefinite period when required.

10 The numeral 23 denotes a socket member provided with contacts which are included in the electric circuit adapted to be controlled by means of the switch. A plug 24 of well known construction is adapted to cooperate 15 with the socket 23 in a manner well understood. An electric cord connects the plug 24 with the toaster or other cooking appliance, not shown, adapted to be controlled by means of the switch. Normally the switch is in open 20 position, as indicated most clearly in Figure 3 of the drawings. The extension 17 of the member 4 engages the low portion of the cam 16a. Rotation of the shaft 10 through a small arc effects a lifting of the member 4 and a closing 25 of the switch by bringing the contact 3 in engagement with the contacts 2. As the shaft 10 is rotated, the spring 13 is tensioned to effect movement of the timing mechanism. The shaft 10 may be rotated through a greater or 30 less arc depending upon the length of time it is desired to have the circuit remain closed. The degree of rotation of the shaft 10 may be determined by indications on the case, as shown most clearly in Figure 1 of the drawings.

35 The winding of the electromagnet 19 is preferably included in the circuit controlled by means of the switch. A slight rotation of the shaft 10 effects a closing of the switch, 40 and when said shaft is released from the rotating influence it is reversed by the action of the power spring 13. The speed of the timing mechanism is governed by the action of the magnet 19 upon the disc 18, and as the 45 shaft 10 assumes a normal position the stop 9 on the cam 16a fast to said shaft trips the latch 8, thereby releasing the member 4 which is moved by the spring 7 to open the switch, thereby breaking the circuit of the electric 50 appliance with which the time switch is associated. When the shaft 10 is rotated a complete revolution the latch 20 may be engaged with the stop 21, thereby holding the switch in closed position for any length of 55 time. The circuit may be maintained in closed position for any determinate length of time by rotating the shaft 10 through a given arc which may be determined by the scale indications on the case, as herein set forth.

60 Having thus described the invention, we claim:

65 A time switch including fixed and movable circuit closing contacts, a longitudinally movable bar carrying the movable contact, means supporting, guiding and directing the

bar in its movements, means yieldably holding the bar at the limit of its movement in one direction with the contacts separated, a latch adapted to hold the bar at the limit of its movement in the opposite direction with the contacts in engagement, a cam for moving the bar to close the circuit and in turn limited in its movement in one direction by the bar, a stop carried by the cam for tripping the latch, an operating spring tensioned by movement of the cam to close the switch, and a train of gearing actuated by the operating spring and including means for regulating the return of the cam to normal position.

70 In testimony whereof we affix our signatures.
